UNITED STATES PATENT OFFICE.

CHRISTIAN WILLIAM MEINECKE, OF JERSEY CITY, NEW JERSEY.

DESIGN FOR A POT OR JAR.

SPECIFICATION forming part of Design No. 20,490, dated January 27, 1891.

Application filed December 18, 1890. Serial No. 375,143. Term of patent 7 years.

To all whom it may concern:

Be it known that I, CHRISTIAN WILLIAM MEINECKE, a citizen of the United States, residing at Jersey City, in the county of Hudson and State of New Jersey, have invented and produced a new and original Design for a Pot or Jar, of which the following is a specification.

This design has for its object to provide a novel and ornamental jar or pot for ointment, pomatum, and the like; and its leading features consist in a body having wave-like ridges or corrugations and an upper and a lower band.

In the drawing, the figure is a side elevation of the jar or pot.

The letter A indicates the jar or pot body; ¹⁵ a, the wave-like ridges or corrugations; b, the lower band, and c the upper band.

What I claim is—

The design for a jar or pot, substantially as shown and described.

In testimony whereof I have hereunto set my hand in the presence of two subscribing witnesses.

CHRISTIAN WILLIAM MEINECKE.
